Primary Examiner — Wan Laymon(74) *Attorney, Agent, or Firm* — Henry M. Feiereisen LLC;
Urusula B. Day(57) **CLAIM**

The ornamental design for a sensor cap, as shown and described.

DESCRIPTION

FIG. 1 is a top-front-left side perspective view showing our new design;

FIG. 2 is a top-rear-right side perspective view thereof;

FIG. 3 is a front elevational view thereof;

FIG. 4 is a rear elevational view thereof;

FIG. 5 is a left side elevational view thereof; and,

FIG. 6 is a right side elevational view thereof.

The broken lines are for purposes of modeling the sensor cap on a mannequin and form no part of the design.
